UNITED STATES PATENT OFFICE.

RONELLO F. PRATT, OF REVERE, AND CHARLES D. WAINWRIGHT, OF MEDFORD, MASSACHUSETTS, ASSIGNORS TO THE WAINWRIGHT MANUFACTURING COMPANY, OF PORTLAND, MAINE.

FEED-WATER HEATER.

SPECIFICATION forming part of Letters Patent No. 388,916, dated September 4, 1888.

Application filed June 22, 1887. Serial No. 242,177. (No model.)

To all whom it may concern:

Be it known that we, RONELLO F. PRATT, a citizen of the United States, residing at Revere, in the county of Suffolk and State of Massachusetts, and CHARLES D. WAINWRIGHT, a citizen of the United States, residing at Medford, in the county of Middlesex and State of Massachusetts, have invented a new and useful Improvement in Feed-Water Heaters and Purifiers, of which the following is a specification.

Our invention relates to certain improvements in feed-water heaters and purifiers in which the exhaust steam from the engine is utilized to heat and purify the water fed to the boiler; and the invention consists of pipes arranged one within the other and inclosed within two casings, one forming a water-chamber and the other a steam-chamber, as hereinbelow fully described, and pointed out in the claims.

Referring to the accompanying drawings, Figure 1 is a vertical section of a feed-water heater and purifier embodying our invention. Fig. 2 is a horizontal section taken on line *xx* of Fig. 1. Fig. 3 is a horizontal section through the divided water-chamber.

A is a hollow base of cast-iron divided horizontally by a partition, B, so as to form two chambers, C D. Upon the top of this base-piece is secured a tube-plate, E, on which is secured a casting, F, with a partition across its center, forming two chambers, G G'. The chamber G is in communication with the chamber C by means of a pipe, H.

To the tube-plate E is secured a series of vertical spirally-corrugated tubes or pipes I I, closed at their upper ends by caps or plugs, and to the casting F is secured the ends of vertical spirally-corrugated tubes or pipes J, arched over at the top, so that one end is connected to communicate with the chamber G while its other end communicates with the chamber G'. The tubes I pass up inside the tubes J, as shown. These spirally-corrugated tubes are inclosed in a casing, K, that forms a chamber for the steam to pass through, and the casing K is inclosed in an outer shell or

casing, L, the space between the two casings K L forming a water-chamber. The casing K is provided at its lower end with a wide flange, k, that is secured by bolts to the base A, and to this flange k is also secured the outer casing, L, as shown. On the top of the outer casing, L, is secured a dome, M, and within this dome is a pipe, N, secured at its lower end to the top plate, K', of the casing K, and its upper end passing out of the top of the dome M, as shown.

Cold water is admitted at P into the chamber C and passes up the pipe H into the chamber G, thence up the tubes J, (on the outside of tubes I,) over the arched top, and down on the opposite side into the chamber G', from which it passes by a pipe, Q, into the water-chamber R between the two casings K L, and from which it passes to the boiler by a pipe, S.

The exhaust-steam is admitted at T into the chamber D, and passes up the tubes I inside the tubes J, and also into the chamber U around the outside of the tubes J, and thence out of the pipe N. The exhaust-steam entering the chamber D and passing up the tubes I, and also through the chamber U while the water is passing through the tubes J and up the chamber R, heats the water to about 212° Fahrenheit, and as the carbonate of lime commences to throw off carbonic-acid gas, as the temperature is raised above 165° Fahrenheit, the carbonic acid gas passes up into the dome M and escapes by a pipe, W, while the carbonate of lime is precipitated and the heavier particles fall to the bottom.

It will be seen that the steam entering the tubes I cannot pass through them, they being stopped at the top by a cap or plug. Consequently the lightest steam will always ascend to the top and the water passing around them in the tubes J, while steam surrounds the latter, a very high degree of temperature is imparted to the water before it passes into the chamber R, where it is kept hot by the steam in the chamber U.

Should any scale be deposited upon the tubes I J, the expansion and contraction of the said tubes will render them self-cleaning, so

that they are automatically freed from scale without injury to their connections.

By the employment of the spirally-corrugated tubes a much greater heating-surface is obtained than with plain tubes occupying the same space, therefore rendering them much more effective in heating; and as the corrugations form a succession of arches, both longitudinally and transversely, the strength of the tubes is much greater. Therefore a thin tube can be used, which gives greater efficiency in the transmission of the heat, and consequently a great saving in fuel.

Instead of the spirally corrugated tubes, angular corrugated tubes or plain tubes may be employed, but not with such beneficial results.

What we claim as our invention is—

1. In a feed-water heater and purifier, a series of tubes arched at the top and secured at their lower ends to a divided water-chamber, and provided with internal vertical stopped tubes, all of which are inclosed within suitable steam and water chambers, substantially as shown and described.

25 2. In a feed-water heater and purifier, an

outer water-chamber inclosing a steam-chamber in which are placed arched pipes secured at their lower ends to a divided water-chamber, and provided with internal vertical stopped tubes secured to a base-plate and communicating with the exhaust steam chamber, substantially as shown and described.

3. In a feed-water heater and purifier, the steam chamber U, inclosed within the water-chamber R and provided with arched pipes 35 J J, secured at their lower ends to a divided water-chamber, G G', in combination with vertical stopped tubes I, secured to base-plate E, the exhaust steam chamber D, water-chamber C, and pipe H, substantially as shown and 40 described.

In testimony whereof we have signed our names to this specification in the presence of two subscribing witnesses.

RONELLO F. PRATT.
CHARLES D. WAINWRIGHT.
